UNITED STATES PATENT OFFICE.

THOMAS E. BRALEY, OF WICHITA, KANSAS.

SIREN.

Application filed October 2, 1926. Serial No. 139,115.

My invention relates to improvements in sirens. It is adapted for use on automobiles, air planes and air ships, and is of the type in which a revolving member is provided with blades which produce sound by forcing air through peripheral openings in a casing in which the member is mounted.

One of the objects of my invention is to provide a novel siren of the kind described, which is simple, cheap, durable, not liable to get out of order, and which is reliable in its operation.

A further object of my invention is to provide a siren which in operation will simultaneously produce two sounds of different tones.

My invention provides further a novel construction which permits of the rotation of the revolving member in either direction and to produce like signals when revolved either way, whereby the siren can be adapted to different conditions of the power mechanism which rotates the revolving member.

My invention further provides a novel mechanism for holding the revolving member from rotation by the propelling power, when it is not desired to have the siren sound signals.

The novel features of my invention are hereinafter fully described and claimed.

In the accompanying drawings, which illustrate the preferred embodiment of my invention,

Fig. 1 is a side elevation, partly broken away, of my improved siren.

Fig. 2 is a front elevation of the same.

Fig. 3 is a rear elevation of the same.

Fig. 4 is a section on the line 4—4 of Fig. 1.

Fig. 5 is a section on the line 5—5 of Fig. 2.

Fig. 6 is a section on the line 6—6 of Fig. 1.

Fig. 7 is a side elevation of the revolving member.

Similar reference characters designate similar parts in the different views.

The siren has a casing body 1 having at its front end a removable cover 2 fastened to it by screws 3, or other suitable securing means. The casing has a circular chamber having at its rear end an air inlet comprising openings 4, the cover 2 having an air inlet comprising openings 5.

The body 1 of the casing has two sets of circularly arranged peripheral holes 6 and

7, there being in the form shown 8 holes 6 and nine holes 7. In order that two different deep tones or sounds may be simultaneously produced, the numbers of holes of the two sets 6 and 7 must not have a common divisor. For example, if the holes 6 number eight, the holes 7 should not number six or ten, or have any number having a common divisor with number eight, otherwise there will be no simultaneous production of different tones.

A horizontal shaft 8 is rotatable in ball bearings 9, mounted one bearing in the rear end of the body 1 and one bearing in the cover 2, Fig. 5.

Secured rigidly to the shaft 8, as by a set screw 9', is a revoluble member 10, which is rotatable in the casing, and which is provided with a partition 11 transverse to the axis of the member 10, and which is located between the openings 4 and 5, and between the two sets of outlets 6 and 7.

Extending radially from the hub of the member 10 at opposite sides of and joined to the partition 11 are two sets of T shaped blades 12 and 13, there being nine blades in the set 13 at the front side of the partition 11, and eight blades in the set 12 at the rear side of the partition. The blades of each set are equally spaced and number the same as the peripheral outlet holes with which they co-operate, and through which they drive air taken into the casing at the adjacent inlet holes. The transverse head portion 15 of each of the blades 12 and 13, extends at equal distances at opposite sides of the radial portion of the blade and is of a width such that it will cover any of the air outlet holes with which it co-operates. By having the two circular portions of the body 1, respectively containing the outlet holes 6 and 7, of different diameters, the one of smaller diameter being the one having the larger number of discharge openings, the difference in pitch of the two deep tones produced will be still further accentuated.

Each head portion 15 has in its outer side a transverse groove 16, with which communicate the outer ends of two holes 17 that extend through the head to the inner side thereof and to opposite sides respectively of the radial portion of the blade. These grooves 16 and holes 17, together with the difference in diameter of the two circular portions of the body 1, enables the production of two different shrill tones.

When the member 10 is rotated in the casing the head portion 15 of the blades 12 and 13 will each consecutively cover and uncover the outlet holes with which it co-operates, 5 and a pleasing and characteristic signal having two different deep tones commingling with two different shrill tones will be made.

By having the blades 12 and 13 T shaped, the member 10 may be revolved in either 10 direction and produce the same signals.

The power conditions sometimes require that the shaft 8 be rotated in one direction or the other, as when the shaft is driven by some rotary part of an automobile.

15 When used with an air plane or an air ship, a propeller 18, may be secured on the shaft 8 to afford the driving power therefor.

If the device is used on an automobile, it may be connected with some rotary part of 20 the machine, as the fan driving shaft, by a belt and pulley, not shown, or other suitable transmission mechanism.

In order that the member 10 may be held 25 from rotation, excepting when it is desired to operate the siren, I provide a brake block 19 which is reciprocative in a hole 20 in the body 1, and which has a stem 21 slidable in a hole through the cover 2 and a cylindrical extension 22 on the front side of the cover 30 2. The rear end of the brake shoe or block 19 is normally held with sufficient pressure against the partition 11 to hold the latter from revolving, by a coil spring 23, which at 35 its rear end bears on the partition 11 and at its front end against the cover 2.

To withdraw the shoe 19 from holding engagement with the partition 11, the stem 21 has fastened to it a flexible member, such as a cord or wire cable 24, which passes over 40 a grooved pulley 25 rotatably mounted on a bracket 26, which has two arms 27 embracing the projection or extension 22. The bracket 26 may be circumferentially adjusted on the projection 22 and then held in its adjusted position by tightening a nut 28, Fig. 2, on a bolt 29, which extends through the arms 27. By utilizing an operating member, such as the cable 24 attached to the stem 21 of the brake shoe, the pressure of the latter against the partition 11 may be varied 50 without entirely releasing the brake shoe.

In the operation of the siren, when the shaft 8 is rotated and with it the member 10 the air will be drawn into the casing through 55 the openings 4 and 5, and discharged by the blades 12 and 13 through the openings 6 and 7 respectively, two tones being made at the same time, when the member 10 is rotated with the rapidity required for its successful operation.

It will be noted that the grooves 16 in the outer sides of the head portions 15 of the blades do not extend to the full width of the head portions, but only to the edges 60 distant from the partition, thus preventing

air from passing from the grooves to between the partition 11 and the brake shoe 19.

The casing may be supported in any suitable manner. For receiving a supporting bar, not shown, the body 1 is provided at its 70 rear end near the bottom with a transverse hole 30 which is intersected by a vertical groove 31 adapted to receive a pin, not shown in said supporting bar.

I do not limit my invention to the structure shown and described, as many modifications, within the scope of the appended claims, may be made without departing from the spirit of my invention. 75

What I claim is:—

1. In a siren of the kind described, a casing having an air inlet and circularly arranged air outlets, an air driving member rotatable in said casing and provided with circularly arranged blades each having a head portion which, on the rotation of said member, consecutively covers and uncovers said air outlets, each of said head portions having an air passage therethrough extending from the inner side of the head portion 90 at one side of the blade to the outer side of said head portion and disposed so as to consecutively communicate with said outlets, and means for supporting and rotating said member. 95

2. In a siren of the kind described, a casing having an air inlet and circularly arranged air outlets, an air driving member rotatable in said casing and provided with circularly arranged blades, each having a head portion which, on the rotation of said member, consecutively covers and uncovers said outlets, each of said head portions having on its outer side a transverse groove, each head portion having an air passage extending therethrough from the inner side thereof to said groove in said head portion, and means for supporting and rotating said member. 100

3. In a siren of the kind described, a casing having an air inlet and circularly arranged air outlets, an air driving member rotatable in said casing and having circularly arranged T shaped blades, the transverse head portion of each of said blades, on the rotation of said member, consecutively covering and uncovering said outlets, each of said head portions having two air passages extending therethrough from the inner side thereof at opposite sides respectively of said 110 blade to the outer side of said head portion, and means for supporting and rotating said member. 120

4. In a siren of the kind described, a casing having an air inlet and circularly arranged air outlets, an air driving member rotatable in said casing and having circularly arranged T shaped blades, the transverse head portion of each of said blades, on the rotation of said member, consecutively cover- 125 130

ing and uncovering said outlets, each head portion on its outer side having a transverse groove, each of said head portions having therethrough two air passages extending 5 from opposite sides respectively of the blade to said groove, and means for supporting and rotating said member.

5. In a siren of the kind described, a casing having an air inlet and circularly arranged 10 air outlets, an air driving member rotatable in said casing and having means, when rotated for driving air through said outlets, said member having an extension provided with a hole therethrough, means for 15 supporting and rotating said member, a brake shoe reciprocative in said hole and adapted to bear against and hold said member from rotating, means for normally forcing 20 said brake shoe into holding engagement with said member, a bracket circumferentially adjustable on said extension, a pulley 25 rotatable on said bracket, and a flexible operating member attached to said brake shoe and engaging said pulley and adapted when pulled to withdraw said brake shoe from holding engagement with said member.

6. In a siren of the kind described; a casing having two air inlets and two sets of circularly arranged air outlets, the numbers 30 of said outlets in said two sets not having a common divisor, an air driving member rotatable in said casing and having a partition transverse to its axis between said sets, and at opposite sides of said partition having 35 respectively two sets of blades adapted, when the member is rotated to respectively force air through said two sets of outlets, each set of blades and the set of outlets with which they co-operate being spaced 40 equally apart and having like numbers, and means for supporting and rotating said member.

7. In a siren of the kind described, a casing having two air inlets and two sets of circularly arranged air outlets, the numbers 45 of said outlets in said two sets not having a common divisor, an air driving member rotatable in said casing and having a partition transverse to its axis between said inlets 50 and between said two sets of outlets, and at opposite sides of said partition being provided respectively with two sets of blades, adapted when said member is rotated to respectively force air through said two sets of 55 outlets, each of said sets of blades and the set of outlets with which it co-operates having a like number and equally spaced, each

of said blades having at its outer end a transverse portion adapted to consecutively cover and uncover the adjacent outlets, when 60 said member is rotated, and means for supporting and rotating said member.

8. In a siren of the kind described, a casing having two circular portions of different diameters and having respectively two sets of circularly arranged equally spaced air outlets, the numbers of said outlets in said two sets not having a common divisor, and a rotary air driving member in said casing having two sets of blades respectively co- 70 operating with said two sets of outlets and having respectively like numbers and being equally spaced, said member having a partition transverse to its axis intermediate of said two sets of blades. 75

9. In a siren of the kind described, a casing having an air inlet and air outlets, an air driving member rotatable in said casing having means for driving air through said outlets, a brake shoe, means for automatically forcing said shoe against said air driving member, a pulley on said casing, and a flexible operating member having running engagement with said pulley and attached to said shoe for retracting the shoe from said 80 driving member. 85

10. In a siren of the kind described, a casing, a pulley, means circumferentially adjustable on said casing and supporting said pulley, an air driving member rotatable in 90 said casing, a brake shoe, means for automatically forcing said brake shoe against said air driving member, and a flexible member having running engagement with said pulley and attached to and arranged to retract said shoe from said driving member. 95

11. In a siren of the kind described, a casing having two sets of peripheral air outlets, the numbers of said two sets not having a common divisor, and a rotary member in 100 said casing having two sets of blades arranged to respectively cooperate with said two sets of outlets to force air therethrough, to produce two tones not in harmony with each other, but which combined effect a discordant sound. 105

12. In a siren of the kind described, a casing having two sets of air passages not having a common divisor, and means for forcing air through said passages so as to produce two tones which do not harmonize. 110

In testimony whereof I have signed my name to this specification.

THOMAS E. BRALEY.
